(57) **CLAIM**

The ornamental design for a profile of a level, as shown and described.

DESCRIPTION

FIG. 1 is a top perspective view of a profile of a level showing the ornamental design.

FIG. 2 is a top plan view of FIG. 1.

FIG. 3 is a front elevation view of FIG. 1, the rear view being a mirror image.

FIG. 4 is a bottom plan view of FIG. 1; and,

FIG. 5 is a right-end elevation view of FIG. 1, the left-end view being a mirror image.

The broken lines are provided for illustrative purposes only and form no part of the claimed design.
